US0D1111934S

(12) **United States Design Patent** (10) Patent No.: **US D1,111,934 S**
(45) Date of Patent: ** Feb. 10, 2026

(54) **ALL-TERRAIN VEHICLE**

(71) Applicant: **ZHEJIANG CFMOTO POWER CO., LTD.**, Hangzhou (CN)

(72) Inventors: **Kai Li**, Hangzhou (CN); **Xiaoying Lv**, Hangzhou (CN); **Chengyao Liang**, Hangzhou (CN); **Ze Wang**, Hangzhou (CN)

(73) Assignee: **ZHEJIANG CFMOTO POWER CO., LTD.**, Hangzhou (CN)

(**) Term: **15 Years**

(21) Appl. No.: **29/973,330**

(22) Filed: **Nov. 15, 2024**

(30) **Foreign Application Priority Data**

May 17, 2024 (CN) 202430294271.7
